UNITED STATES PATENT OFFICE.

ELIJAH A. ANDREWS, OF NEW BRITAIN, CONNECTICUT.

IMPROVED SNAP-HOOK.

Specification forming part of Letters Patent No. 55,219, dated June 5, 1866.

To all whom it may concern:

Be it known that I, ELIJAH A. ANDREWS, of New Britain, county of Hartford, and State of Connecticut, have invented a certain new and useful Improvement in Snap-Hooks; and to enable others skilled in the art to make and use the same, I will proceed to describe its construction and operation, referring to the drawings, in which the same letters marked thereon indicate like parts in each of the figures.

The nature of this improvement will be understood from the specification and drawings.

The object desired to be attained thereby is to provide against the possibility of the hook disengaging itself from a ring or staple into which it may be hooked by the twisting or sidewise turning of a ring, &c., against the protecting-latch, which frequently takes place with those now in use, owing to the exposed length of latch back from the hook-point, which objection by the use of this improvement is entirely removed, because only sufficient space is provided between the hook-point and the body of the hook to admit the size of a bit-ring, &c., into the hook-space.

In the accompanying drawings is shown a sectional view of this improvement. *a* is the body of the hook. *b* is the hook proper. *c* is

the strap-loop. *d* is a recess formed in the body between the hook *b* and the loop *c* in the back side. *e* is a latch which is fitted into said recess so as to nearly or quite fill the space *g*, provided to receive the bit-ring, &c., into the hook, and is hung or secured by a pin or rivet, *h*, just forward of the strap-loop *c*. Said latch is provided with a finger-pad, *i*, just back of its fulcrum-pin, and is underlaid with a pressure-spring, *n*, which acts to reclose the latch after it has been opened by the pressure of the finger upon the pad *i*. This latch is finished on the outside even with the body of the hook, so as to give a good symmetrical appearance.

I believe I have thus shown the nature, construction, and advantage of this improvement so as to enable others skilled to make and use the same.

I claim—

The combination of the latch *e*, within and flush with the back of the recess *d* relative to the opening *g*, with the pad *i*, spring *n*, and loop *c*, substantially as and for the purpose described.

ELIJAH A. ANDREWS. [L. S.]
